UNITED STATES PATENT OFFICE.

ROBERT W. RICE, OF CLEVELAND, OHIO.

OZONE-GENERATOR.

950,347.

Specification of Letters Patent. Patented Feb. 22, 1910.

Application filed October 25, 1909. Serial No. 524,406.

To all whom it may concern:

Be it known that I, ROBERT W. RICE, a citizen of the United States, residing at Cleveland, in the county of Cuyahoga and State of Ohio, have invented certain new and useful Improvements in Ozone-Generators; and I do declare the following to be a full, clear, and exact description of the invention, such as will enable others skilled in the art to which it appertains to make and use the same.

This invention relates to improvements in ozone generators.

One object of the invention is to provide a simple and improved construction of ozone generator by means of which air passing into contact therewith will be purified or converted into ozone.

Another object is to provide a device of this character the construction and arrangement of which provides for or permits the capacity of the generator to be increased or diminished when desired.

With the foregoing and other objects in view, the invention consists of certain novel features of construction, combination and arrangement of parts, as will be more fully described and particularly pointed out in the appended claims.

In the accompanying drawings: Figure 1 is a vertical sectional view through a box or casing, showing my improved generator arranged therein; Fig. 2 is a horizontal sectional view through the casing, showing a top plan view of one of the generator sections; Fig. 3 is an enlarged vertical sectional view through one of the sections of the generator; and Fig. 4 is a detail fragmentary sectional view of two sections of the generator, showing the manner in which the sections are engaged with each other.

In the embodiment of my invention, I provide a suitable box or casing 1, which is divided into upper and lower compartments by a transverse partition 2. The casing 1 is provided with suitable openings to permit the passage of air therethrough. In the lower compartment of the casing 1 is arranged a transformer 3, which is connected by conducting wires 4 to a suitable electric generator.

In the upper compartment of the casing is arranged my improved ozone generator, which is formed of one or more sections, each of which consists of a central plate 5

of glass or other dielectric material. Arranged on and engaging the opposite sides of the glass plate 5 are perforated aluminum, platinum or other metal plates 6. The perforations in said plates are punched through the same and the punched metal forms projecting points which engage or bear against the opposite sides of the glass plate 5 and thus space the platinum plates a suitable distance therefrom.

The platinum and glass plates are held together in proper position by means of clamping frames 7, which are formed of metal and are preferably constructed as shown in Fig. 2 of the drawings. Along the opposite sides of the plate 7 are formed laterally projecting upwardly curved arms or fingers 8 provided near their outer ends with annular grooves with which are engaged rubber bands 9. The rubber bands 9 serve to clamp the frames 7 into engagement with the plates 6 and thus hold the latter in proper engagement with the glass plate 5. On the outer sides of the arms 8 of one of the plates 7 are formed outwardly projecting studs 10, which are adapted to engage sockets 11 formed in the arms of the adjacent plates of the adjoining section of the generator, said studs and sockets holding the stack of sections in position in the box or casing 1. The lowermost section of the stack is preferably supported on suitable projections 12 arranged on the partition 2 of the casing, as shown.

It will thus be seen that any number of generator sections may be arranged in the box or casing 1, thus increasing or diminishing the capacity of the device. The upper and lower platinum plates 6 of each of the generator sections are connected to current conducting wires 13, which extend upwardly from the transformer through a suitable passage 14 in the partition 2 being connected with the plates 6 along one side of the section, as shown. By means of the transformer 13 a high potential current may be produced and conducted to the platinum plates 6 which engage the dielectric plate 5 and cause a blue flame to be emitted from the perforations so that the air passing through the box or casing and into contact with the generators is purified or converted into ozone.

From the foregoing description, taken in connection with the accompanying drawings,

the construction and operation of the invention will be readily understood without requiring a more extended explanation.

Various changes in the form, proportion and the minor details of construction may be resorted to without departing from the principle or sacrificing any of the advantages of the invention, as defined in the appended claims.

10 10 What I claim is:

1. In a device of the character described, a plate formed of dielectric material, perforated electrode plates arranged on opposite sides of said dielectric plate, said electrodes having formed thereon a series of points which engage the opposite sides of said dielectric plate, clamping frames adapted to hold said electrode plates in position, arms formed on the opposite edges of said plates, rubber bands engaged with said arms whereby the clamping plates are held in operative engagement with the electrode plates, and means on said arms to engage the arms of the clamping plates of an adjacent generator.

2. In a device of the character described,

a casing having formed therein compartments, a transformer arranged in one of said compartments, a series of generator sections arranged in the opposite compartment, said sections each comprising a plate of dielectric material, perforated platinum plates arranged on opposite sides of said dielectric plate, clamping frames to hold said plates in operative position, arms formed on the opposite edges of said clamping frames, the arms of one of said frames having formed therein sockets, studs formed on the arms of the frames and the adjacent section and adapted to engage said sockets whereby the sections are held in position in said casing, and rubber bands engaged with the arms of said frames whereby the latter are held in clamped engagement with the plates forming the sections.

In testimony whereof I have hereunto set my hand in presence of two subscribing witnesses.

ROBERT W. RICE.
